UNITED STATES PATENT OFFICE.

JACK KATZ, OF NEW YORK, N. Y.

DESIGN FOR A CANDLESTICK.

Application filed March 25, 1927. Serial No. 21,325. Term of patent 3½ years.

To all whom it may concern:

Be it known that I, JACK KATZ, a citizen of the United States, and residing at New York, in the county of New York and State of New York, have invented a new, original, and ornamental Design for a Candlestick, of which the following is a specification, reference being had to the accompanying drawings, forming part hereof.

The figure is a perspective view.

I claim:

The ornamental design for a candlestick as shown.

JACK KATZ.
